Dec. 470

William F. Pratt & George W. Bosworth of Milford N.H.
Letters Patent No 470 Dated July 13th 1852

The schedule referred to in these Letters Patent and making part of the same

To all ^{Persons} to whom these presents shall come:

Be it known that we, William F. Pratt
and George W. Bosworth of Milford in the County of Hilleborough and
State of New Hampshire, have invented or produced a new and ornamental
design for a Cooking Stove, and we do hereby declare that the same
is represented in the accompanying drawings.

Of the said drawings Figure 1. denotes
the ornamental configuration of one side of the stove as seen in elevation;
Figure 2. that of the front, and Figure 3. that of the rear of the stove under similar
circumstances. Figure 4 is a vertical section of the front plate, the same being
taken through one of the fire placed doors. Figure 5 is a vertical section of the middle
part of the back plate. Figure 6 is a vertical section of the side plate, the said
section being taken through the middle of the ornamental bas relief of the larger
door of the said plate.

The words "AIR TIGHT" as shown on
the front plate constitute no part of the above mentioned new ornamental
design, it being made up of the ornamental onouldings, panels, stars, &
configurations, as exhibited in the several drawings above mentioned.

In the panel of the larger door of the
side plate Figure 1, there will be seen a star projecting in bas relief from a
shield that has a series of lance heads extended in radial lines from it.

What we claim as our invention or
production is the ornamental design for a cooking stove substantially as
represented in the accompanying drawings.

And we also particularly claim
the combination of the star, shield, and radial lance heads as exhibited in
the panel of the larger door of the side plate.
